ELECTRIC SWITCH

George J. Meuer, Milwaukee, Wis., assignor to
Cutler-Hammer, Inc., Milwaukee, Wis., a corporation of Delaware

Application November 18, 1940, Serial No. 366,105

8 Claims. (Cl. 200—172)

This invention relates to improvements in electric switches. The invention relates more particularly to improvements in toggle operated snap switches of the tool-handle type.

An object is to provide a switch operating lever having novel means for pivotally supporting and guiding the same whereby wobbling or lateral displacement of the lever is substantially prevented.

Other objects and advantages of the invention will hereinafter appear.

The accompanying drawings illustrate certain embodiments of the invention which will now be described, it being understood that the embodiments illustrated are susceptible of modification in respect of certain details of construction thereof without departing from the scope of my invention as defined in the appended claims.

In the drawings, Figure 1 is a top view (normal size) of a toggle lever operated snap switch of the tool-handle type, said switch having novel means for mounting the same in a tool-handle or the like, and the same having elements applied thereto to render the same substantially dust-tight.

Fig. 2 is a sectional view (double-scale), on the line 2—2 of Fig. 1.

Fig. 3 is a sectional view, on the line 3—3 of Fig. 1.

Fig. 4 is a view (normal size), partly in side elevation and partly in vertical section, illustrating a switch generally similar to the switch of Figs. 1 to 3, but having mounting means of modified form applied thereto.

Fig. 5 is an end elevation, partly in vertical section on the line 5—5 of Fig. 4.

Fig. 6 is a fragmentary vertical sectional view of the pivotal supporting and guiding means for the toggle lever shown in Figs. 1 to 5.

Fig. 7 is a view quite similar to Fig. 3, but illustrating a modified form of tubular member affording a wide pivotal support for the lever, which tubular member also acts to prevent substantial lateral displacement of the lever, the sheet metal top plate being provided with an opening of sufficiently large size to accommodate the ball or knob after attachment of the latter to the lever, and

Fig. 8 is a fragmentary view, partly in elevation and partly in vertical section, showing my improved tubular member attached to a lever to afford a wide pivotal support, and to limit the lever to oscillatory movement in a single plane, when associated with the externally threaded bushing of a one-hole mounting type of switch.

This application is a continuation in part of my application, Serial No. 233,828, filed October 7, 1938, for improvements in Electric switches, now Patent No. 2,247,247, dated June 24, 1941.

Referring first to Figs. 1 to 3 and 6, wherein I have illustrated a toggle lever snap action switch of the tool-handle type having an alternating current controlling capacity of 10 amperes at 250 volts or 12 amperes at 125 volts, it is to be understood that the switch mechanism embodies certain features described and claimed in my prior Patents No. 1,889,259, dated Nov. 29, 1932; No. 1,977,078, dated Oct. 16, 1934; and No. 2,089,032, dated Aug. 3, 1937; reference being had to said prior patents for a detailed description of certain of the switch parts.

Here, as in said prior patents, I provide a molded insulating base, designated in general by the numeral 15, said base having a recess 16 (Fig. 2) opening to the upper surface thereof. Base 15 is provided with a rib whose flat surface 17 (Fig. 2) is offset upwardly from the bottom wall of recess 16. Slidable upon surface 17 is a flat punched insulating plate 18 which carries a pair of like contactors arranged on opposite sides of said rib. One of said contactors is shown at 19 as comprising a metal strip bent to substantially U-shape, whereby the arms thereof are exposed on the upper and lower surfaces of plate 18. Said contactors are rigidly and permanently secured to plate 18 as by means of rivets, one of which is shown at 20. A pair of upper and lower resilient stationary contacts 21 and 22 is positioned on each side of the aforementioned rib 16, the respective contacts being secured to ledges offset downwardly from the upper surface of base 15 as by means of a corresponding number of internally threaded eyelid members which provide for bottom wiring of the switch, in the manner illustrated in Fig. 4, of my aforementioned Patent No. 2,089,032. Two of the wiring terminal screws are shown herein at 23 in Fig. 3.

The toggle snap action mechanism for the switch comprises a wire yoke member 24 pivotally supported above base 15 but depending into the recess 16; a toggle operating lever 25 pivotally supported above yoke 24; a flat punched insulating plate 26 pivotally supported by said yoke, the lower end of plate 26 projecting into a slot or opening 18a in plate 18 to provide a lost motion driving connection between said plates. A coiled spring 27 is interposed under compression between the lower end of lever 25 and plate 26, a portion of which telescopes into the lower end of

said spring. Spring 27 carries at its upper end a metal cup 28 for engagement by said lower end of lever 25.

A flat metal plate 29 is superimposed upon the upper surface of base 15, a flat punched or sheared plate or piece of resilient, rubber-like material 30 being interposed between plate 29 and the upper surface of base 15. Plates 29 and 30 are provided with aligned centrally located openings 29^a, 30^a (Fig. 2) which provide oscillating clearance for yoke 24 and the aforementioned parts associated therewith. Superimposed upon plate 29 is a sheet metal top plate the peripheral flange portion of which is designated by the numeral 31 in Figs. 2 and 3, said top plate having a centrally located portion 31^a of substantially dome-shape. Dome-shaped portion 31^a is provided at its upper end with a relatively narrow opening or slot 31^b extending in a direction longitudinally of base 15, opening 31^b having a width to rather closely accommodate lever 25 comprising a flat sheet metal punching, and the length of opening 31^b being such as to provide a rather close oscillating clearance for the arc-shaped portions 25^b forming an enlargement of said lever. Opening 31^b thus serves to guide lever 25 for oscillatory movement in a single plane, whereas said portions 25^b of the lever insure substantial closure of said opening 31^b under all conditions.

Dome-shaped portion 31^a is provided adjacent to the lower end thereof with aligned openings 31^c, 31^d (Fig. 3) into one of which an outwardly bent end of one arm of yoke 24 is freely insertable, the bent end of the other arm of said yoke being insertable into the other opening by temporarily bending the yoke arms toward each other. Portion 31^a is provided adjacent to the upper end thereof with aligned openings 31^e, 31^f which are respectively vertically aligned with openings 31^c and 31^d. Openings 31^e, 31^f are adapted to receive a pin 32 of circular form in transverse cross section, said pin having a head 32^a engaging the exterior of one side of portion 31^a and a hollow shank end 32^b which is upset over the exterior of the other side wall of said portion 31^a. Pin 32 freely penetrates the passage of corresponding circular form in transverse cross section provided in a relatively long metal member 33 to provide a relatively wide area of bearing engagement between the latter and said pin. Member 33 is provided at its mid-length with a portion 33^a of exteriorly polygonal form (preferably square, as best shown in Fig. 2) in transverse cross section. Lever 25 is provided with an opening 25^c to accommodate, with a rather close sliding fit, the portion 33^a, said portion 33^a extending beyond each side of lever 25, and the material of said portion being upset against opposite sides of lever 25, as shown at 33^b in Figs. 3 and 6, to rigidly and permanently secure said parts in assembled relation.

In practice the pin 32 is free to oscillate or rotate within the aforementioned openings 31^e, 31^f (Fig. 6), but pivotal movement of lever 25 is afforded primarily by the bearing engagement of tubular member 33 with pin 32. By reason of the rigid connection between lever 25 and member 33 and the relatively wide area of bearing engagement of the latter with pin 32 lateral tilting or wobbling of said lever is prevented. Also as aforescribed the walls of opening 31^b in dome-shaped portion 31^a cooperate with lever 25 to limit the same to oscillatory movement in a single plane. This insures against accidental

lateral displacement of the lower end of lever 25 from the cup or abutment 28 at the upper end of spring 27.

Many portable tools (such as grinders, polishers or drills) are used under conditions involving the presence of metal dust, stone dust, or other particles in the surrounding air; and if such dust particles have access to the switch chamber they, of course, tend to ruin the switch mechanism and to greatly reduce the useful life of the latter. It is accordingly a primary object of my invention to render the switch chamber substantially dust-tight, and this object is attained in the device of Figs. 1 to 3 by providing a relatively thin walled, dome-shaped insulating member 34 molded from a resilient, rubber-like material. Member 34 and the aforementioned plate 30 may be and preferably are composed of identical resilient, rubber-like material, a preferred form of such material being made and sold commercially under the trade-name of "Neoprene." Such material is extremely live and resilient (or elastic) and is further characterized by its resistance to deterioration under the influence of, or in the presence of, oil or grease.

As best shown in Figs. 2 and 3 member 34 is provided with a slot or opening 34^a which it is to be understood is relatively narrower than the thickness of lever 25 and relatively shorter than the width of the enlarged portion (comprising arcuate portions 25^b) of said lever. Therefore the walls of said opening 34^a will be biased by the resiliency of the rubber-like material into close engagement with the sides and edges of lever 25 in all positions of the latter, the resiliency or elasticity of member 34 being such as to permit bodily deformation or distortion thereof as an incident to oscillatory movement of said lever while maintaining said close connection of member 34 with the latter.

Also as best shown in Figs. 2 and 3 member 34 is provided at its lower end with a flange portion 34^b which overlies the aforementioned top plate 31, said flange portion 34^b being provided with a downwardly extending edge portion or peripheral rib 34^c which surrounds the peripheral edge of top plate 31 and engages the aforementioned metal plate 29. Superimposed upon flange portion 34^b is a metal plate 35 having a relatively large centrally located opening 35^a to accommodate said dome-shaped member 34. Plate 35 has associated therewith a pair of nuts here shown as substantially cylindrical elements having threaded passages 36^a extending therethrough. Elements 36 are provided at their lower ends with reduced portions 36^b adapted to extend downwardly through correspondingly shaped openings in plate 35, the material of said reduced portions being upset over the lower surface of plate 35, as shown at 36^c, to rigidly and permanently secure said nuts to said plate. Elements 36 are provided with further reduced portions 36^d projecting downwardly through corresponding openings in flange portion 34^b and metal top plate 31 to afford a proper degree of engagement of elements 36 with the threaded shanks of a pair of bolts 37 extending upwardly from the bottom surface of base 15.

The flat upper ends of elements 36 are adapted to abut the inner surface of the wall of a cavity provided in a tool-handle or the like (not shown), said wall having openings formed therein to provide clearance for the shanks of mounting screws or bolts which take into the upper ends of the respective threaded passages

36^a. Said cavity wall will of course be provided with a suitable opening to afford oscillating clearance for the upper end portion of lever 25. As shown in dotted lines in Fig. 2 lever 25 is provided at its upper end with a reduced portion 25^d which is adapted for a drive fit within a recess provided in a spherical knob member 25^e. As will be understood, knob 25^e is applied to lever 25 after upward insertion of the latter through the aforementioned opening 34^b in portion 34^a of the top plate. The walls of opening 34^a in the dust-proofing cap 34 are sufficiently elastic to permit downward passage of said cap over knob 25^e and the intermediate portion of said lever.

In the modification shown in Figs. 4 and 5 most of the switch parts are identical with those aforementioned and have been given corresponding numerals of reference. Instead of the plate 35 and nuts 36 aforementioned, the switch is provided with a plate 38, preferably of die cast aluminum, the opposite ends of plate 38 extending beyond the respective ends of base 15 and having openings 38^a, 38^b to accommodate the shanks of securing screws (not shown) which take into suitable tapped openings in the wall of a portable tool housing or handle. Plate 38 is provided with a central opening 38^c to accommodate the dome-shaped dust-proofing cap 34 and the operating lever 39 extending upwardly through the latter, lever 39 having a spherical knob 39^a attached thereto with a drive fit in the manner aforementioned.

Formed integrally with plate 38 and extending upwardly at substantially right angles thereto adjacent the opposite longitudinally spaced sides of opening 38^c are a pair of transverse ribs 38^d and 38^e, said lugs having segmental notches or concavities 38^f, 38^g formed in the upper edges thereof and aligned with each other. Notches 38^f, 38^g provide ample clearance to enable thumb operation of lever 39 in either direction, whereas the high portions of ribs 38^d, 38^e serve to prevent accidental operation of lever 39 or injury thereto in the event of rough or careless usage of the tool to which the switch may be attached. The switch base 15 and its associated parts are attached to plate 38 as by means of a pair of relatively long bolts 40 which penetrate tapped openings provided in the aforementioned ribs 38^d, 38^e, the upper ends of said bolts being upset, as shown at 40^a, to permanently secure the parts in assembled relation.

In the form of the invention illustrated in Fig. 7 certain of the parts may be identical with the corresponding aforementioned parts, and the same have been given like numerals of reference. In Fig. 7, however, the tubular member 41 is made relatively longer than the member 33 of Fig. 3, thus providing a still wider pivotal bearing or support for lever 25 with respect to pin 32. Member 41 is provided at its mid-length with a portion 41^a of square form in transverse cross section to fit closely within a correspondingly shaped opening (not shown in Fig. 7) in lever 25; and the material of portion 41^a being upset against opposite sides of lever 25, as shown at 41^b and 41^c to rigidly and permanently secure lever 25 and member 41 in assembled relation.

The metal top plate 42 is provided with a centrally located hollow projection 42^a of substantially dome-shape, and the ends of member 41 are adapted to fit rather closely (but rotatably) between the opposed inner surfaces of the wall of projection 42^a, to thereby prevent substantial lateral displacement of member 41 and lever 25.

with respect to the top plate 42. Moreover, projection 42^a is provided in its substantially flat upper end 42^b with a substantially circular opening 42^c, the diameter of which opening is at least 5 slightly greater than the diameter of the ball or knob 25^e, to permit upward insertion of the latter through said opening after said knob has been attached to lever 25. This arrangement facilitates or expedites the assembly of the switch parts.

10 The relatively thin-walled, dome-shaped, rubber-like member 43 is substantially like the member 34 aforementioned and performs the function of rendering the switch of Fig. 7 substantially 15 dust-tight. Member 43 is provided with a slot or opening 43^a which is relatively narrower than the thickness of lever 25 and relatively shorter than the width of the enlarged portion of the lever which extends upwardly therethrough. 20 Member 43 is clamped in position by the metal plate or ring 35 which carries the nuts (one of which is shown at 36) for cooperation with the securing bolts (not shown in Fig. 7) as described in connection with the switch of Figs. 1 to 3 and 6. The headed pin 32 has its shank extending through member 41 and through aligned openings in the opposed sides of the projection 42^a of the top plate, the shank end of said pin being upset at 32^b (as aforementioned) to retain said parts in assembled relation.

25 The lever 44 in Fig. 8 has attached thereto, in the manner described in connection with the other switch levers, a tubular member 45 whose opposite ends are adapted to rotatably abut the 30 diametrically opposite curved inner surface portions 46^a and 46^b of an externally threaded tubular bushing 46 which is attached in any usual or well known manner to the hollow bulge or projection 47 of a punched and stamped sheet 35 metal top plate for a switch. A pin 48 penetrates member 45 and aligned openings in the side walls of bushing 46, the head 48^a and upset shank end 48^b of said pin are located in countersinks or recesses in the exterior of bushing 46 to avoid 40 interference thereof with the clamping nut or nuts (not shown) which are usually employed in a switch of the one-hole mounting type.

45 As will be apparent, the tubular member 45 insures a maximum width of pivotal bearing 50 surface for lever 44 with respect to pin 48, whereas the length of member 45 is so related to the inner surface of bushing 46 as to prevent substantial lateral displacement of the same and of lever 44 with reference to the bushing. In this 55 simple manner the lever 44 is substantially restricted to oscillatory movement in a single plane. Lever 44 preferably has a ball or knob 25^e attached to the upper end thereof in the manner aforementioned.

60 I claim:

1. In an electric switch of the tool-handle type, in combination, a punched and stamped sheet metal top plate having a flat peripheral flange and a substantially centrally located dome-shaped portion extending upwardly from said flange, said dome-shaped portion having a relatively narrow opening formed in the upper end thereof, a flat punched sheet metal lever having an intermediate portion located within said opening and oscillatable with respect thereto, said lever having an opening of polygonal contour formed therein, a tubular metal member having an intermediate portion of a contour closely corresponding to said opening and slidably insertable thereinto, the material of said intermediate

portion of the tubular member being upset against opposite sides of said lever to retain said parts in assembled relation, said dome-shaped portion having alined openings formed in opposite side walls thereof, and a pin freely penetrating said openings and said tubular member to provide a pivotal support for the latter.

2. In an electric snap switch of the tool-handle type, in combination, a hollow metal member having a top wall and peripheral side walls, said top wall having a relatively narrow elongated opening formed therein, a flat punched sheet metal operating lever having an intermediate enlarged portion positioned within said opening and guided by the side walls of the latter for oscillatory movement in a single plane, said enlarged portion being adapted to substantially close said opening in all positions of said lever, the lower portion of said lever having a substantially square opening formed therein, a relatively long metal member having a straight passage of substantially circular form in transverse cross section extending therethrough, said metal member being provided at its mid-length with a portion of externally square form in transverse cross section to fit rather closely within said lever opening, said portion of externally square form extending beyond each side of said lever and the material thereof being upset against said sides respectively to retain said parts in assembled relation, said hollow metal member having alined openings formed in opposite side walls thereof, and a headed pin the cylindrical shank of which is freely insertable through said alined openings and through said passage in the metal member to provide a relatively wide bearing for the latter, the shank of said pin having a hollow end which is upset over the exterior of said hollow metal member to permanently secure said pin in assembled relation.

3. In an electric snap switch of the tool-handle type, in combination, a hollow metal member having a top wall and peripheral side walls, said top wall having a relatively narrow elongated opening formed therein, a flat punched sheet metal operating lever having an intermediate enlarged portion positioned within said opening and guided by the side walls of the latter for oscillatory movement in a single plane, said enlarged portion being adapted to substantially close said opening in all positions of said lever, the lower portion of said lever having a substantially square opening formed therein, a relatively long metal member having a straight passage of substantially circular form in transverse cross section extending therethrough, said metal member being provided at its mid-length with a portion of externally square form in transverse cross section to fit rather closely within said lever opening, said portion of externally square form extending beyond each side of said lever and the material thereof being upset against said sides respectively to retain said parts in assembled relation, said hollow metal member having alined openings formed in opposite side walls thereof, a headed pin the cylindrical shank of which is freely insertable through said alined openings and through said passage in the metal member to provide a relatively wide bearing for the latter, the shank of said pin having a hollow end which is upset over the exterior of said hollow metal member to permanently secure said pin in assembled relation, said lever having an upper end portion of reduced width, and a substantially spherical knob having a recess, said reduced

upper end of said lever being insertable with a drive fit into said recess after positioning of said lever within said opening.

4. In an electric switch, in combination, a punched and stamped sheet metal top plate having a relatively narrow opening formed therein, a flat metal lever having an intermediate portion located within said opening and oscillatable with respect thereto, said lever having an opening of polygonal contour formed therein, a one-piece tubular metal member having an intermediate portion of a contour closely corresponding to said opening and slidably insertable thereinto, the material of said intermediate portion of the tubular member being upset against opposite sides of said lever to retain said parts in assembled relation, said top plate having alined openings formed therein, and a pin freely penetrating said openings and said tubular member to provide a pivotal support for the lever.

5. In an electric snap switch, in combination, a hollow metal member having a top wall and peripheral side walls, said top wall having a relatively narrow elongated opening formed therein, a flat metal operating lever having an intermediate enlarged portion positioned within said opening and guided by the side walls of the latter for oscillatory movement in a single plane, said enlarged portion being adapted to substantially close said opening in all positions of said lever, the lower portion of said lever having an opening of polygonal contour formed therein, a relatively long metal member having a straight passage of substantially circular form in transverse cross section extending therethrough, said last mentioned member being provided at its mid-length with a portion of polygonal contour in transverse cross section to fit rather closely within said lever opening, said last mentioned portion extending beyond each side of said lever and the material thereof being upset against said sides respectively to retain said parts in assembled relation, said hollow metal member having alined openings formed in opposite side walls thereof, and a headed pin the cylindrical shank of which is freely insertable through said alined openings and through said passage in said relatively long metal member to provide a relatively wide bearing for the latter, the shank of said pin having a hollow end which is upset over the exterior of said hollow metal member to permanently secure said pin in assembled relation.

6. In an electric snap switch, in combination, a hollow metal member having a top wall and peripheral side walls, said top wall having a relatively narrow elongated opening formed therein, a flat sheet metal operating lever having an intermediate enlarged portion positioned within said opening and guided by the side walls of the latter for oscillatory movement in a single plane, said enlarged portion being adapted to substantially close said opening in all positions of said lever, the lower portion of said lever having an opening of polygonal contour formed therein, a relatively long metal member having a straight passage of substantially circular form in transverse cross section extending therethrough, said last mentioned member being provided at its mid-length with a portion of polygonal contour in transverse cross section to fit rather closely within said lever opening, said last mentioned portion extending beyond each side of said lever and the material thereof being upset against said sides respectively to retain

said parts in assembled relation, said hollow metal member having aligned openings formed in opposite side walls thereof, a headed pin in the cylindrical shank of which is freely insertable through said aligned openings and through said passage in said relatively long metal member to provide a relatively wide bearing for the latter, the shank of said pin having a hollow end which is upset over the exterior of said hollow metal member to permanently secure said pin in assembled relation, said lever having an upper end portion of reduced width, and a substantially spherical knob having a recess, said reduced upper end of said lever being insertable with a drive fit into said recess after positioning of said lever within said opening.

7. In an electric switch, in combination, a metal support member having opposed substantially vertical side walls, a flat metal lever to be positioned between said side walls in equally spaced relationship thereto, said lever having an opening of polygonal contour formed therein, a one-piece tubular metal member having an intermediate portion of a contour closely corresponding to said opening and slidably insertable thereinto, the material of said intermediate portion of the tubular member being upset against opposite sides of said lever to retain said parts

in assembled relation, said side walls of said support member having aligned openings formed therein, and a pin freely penetrating said openings and said tubular member to provide a pivotal support for the lever.

8. In an electric switch, in combination, a metal support member having opposed substantially vertical side walls, a flat metal lever to be positioned between said side walls in equally spaced relationship thereto, said lever having an opening of polygonal contour formed therein, a one-piece tubular metal member having an intermediate portion of a contour closely corresponding to said opening and slidably insertable thereinto, the material of said intermediate portion of the tubular member being upset against opposite sides of said lever to retain said parts in assembled relation, said side walls of said support member having aligned openings formed therein, and a pin freely penetrating said openings and said tubular member to provide a pivotal support for the lever, said tubular member being of a length only slightly less than the distance between said side walls, whereby said lever is substantially limited to oscillatory movement in a single plane.

GEORGE J. MEUER.
